[57] CLAIM

The ornamental design for file assembly, as shown and described.

DESCRIPTION

FIG. 1 is a front elevational view of a file assembly showing my new design;

FIG. 2 is a right side elevational view, the left side being a mirror image thereof;

FIG. 3 is a rear elevational view;

FIG. 4 is a top plan view;

FIG. 5 is a bottom plan view;

FIG. 6 is a side elevational view of a modified form of the design shown in FIGS. 1 through 5, the opposite side being a mirror image thereof; and

FIG. 7 is a front elevational view of FIG. 6.

FIG.1.

FIG.2.

FIG.4.

FIG.3.

FIG.5.
